CLAIM

The ornamental design for an otoscope as shown and described.

DESCRIPTION

FIG. 1 is a rear, left and top perspective view of an otoscope showing our design;

FIG. 2 is a front, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view of another state of the otoscope thereof.

The broken lines are included for the purposes of illustrating portions of the otoscope that form no part of the claimed design.
